UNITED STATES PATENT OFFICE.

WILLIS S. JONES, OF CHICAGO, ILLINOIS, ASSIGNOR TO GEORGE WESTINGHOUSE, OF PITTSBURG, PENNSYLVANIA.

DRAW-GEAR AND BUFFING APPARATUS.

SPECIFICATION forming part of Letters Patent No. 742,792, dated October 27, 1903.

Application filed September 16, 1901. Renewed October 2, 1903. Serial No. 175,527. (No model.)

To all whom it may concern:

Be it known that I, WILLIS S. JONES, a citizen of the United States, residing at Chicago, county of Cook, State of Illinois, have invented 5 a certain new and useful Improvement in Draw-Gear and Buffing Apparatus; and I declare the following to be a full, clear, and exact description of the invention, such as will enable others skilled in the art to which it 10 pertains to make and use the same, reference being had to the accompanying drawings, which form a part of this specification.

My invention relates in general to draw-gear and buffing apparatus, and more particularly to that type of such apparatus in which 15 a frictional resistance is produced and exerted to reduce or dissipate the shocks due to the pulling and buffing strain incident to the starting and stopping of a train, and thereby 20 obviate injury to the draw-bar or draft-timbers of the rolling-stock.

The object of my invention is to provide a draw-gear and buffing apparatus of the type referred to in which a series of friction devices are forced into frictional engagement 25 with each other by the pulling or buffing strain and adjacent devices then moved transversely to the line of draft and relatively in different angular directions. The relative 30 transverse movement between adjacent friction devices may be accomplished either by the transverse displacement of one set of alternate devices, while the alternate devices forming a second set are held transversely immovable, or by the vertical displacement of 35 one set of alternate devices, while the other set of alternate devices are displaced horizontally, or by the vertical displacement of one set of alternate devices due to the elevation 40 of one side and the depression of the other side of each device, while the second set of alternate devices are either moved transversely in an opposite direction or are held transversely immovable or are displaced horizontally. 45

A further object of my invention is to provide an apparatus of the character referred to in which the desired retardation is produced by a series of friction devices located 50 in each end of a casing, adjacent devices in

both series being relatively moved in different angular directions whenever a pulling or buffing strain occurs.

A further object is to augment the retardation by subjecting a compression-spring interposed between said series of devices to a torsional strain through the engagement of its opposite ends with the inner friction devices of the two series, such devices being rotated slightly in opposite direction in parallel vertical planes.

My invention will be more fully described hereinafter with reference to the accompanying drawings, in which the same is illustrated as embodied in several convenient and practical forms, and in which—

Figure 1 is a longitudinal section through a draw-gear and buffing apparatus embodying my invention; Fig. 2, a view similar to Fig. 1, showing the parts of the apparatus in the positions they assume when subjected to a pulling strain; Fig. 3, an end view of the casing or housing, showing guides for displacing alternate friction devices; Fig. 4, a perspective view of one end of the casing, showing the same arrangement of the guides as Fig. 3; Fig. 5, a perspective view similar to Fig. 4, illustrating a modified arrangement of the guides; Fig. 6, a view similar to Figs. 4 and 5, showing still another modified arrangement of the guides, a portion of the upper wall of the casing being broken away to better illustrate the top guides; Fig. 7, a view similar to Fig. 1, showing a modified arrangement of the guides; Fig. 8, a view similar to Fig. 3, showing the arrangement of the guides in the modification shown in Fig. 7; and Fig. 9 a view similar to Figs. 4 and 6, showing the arrangement of the guides illustrated in Figs. 7 and 8. 90

Similar reference characters are used to indicate similar parts in the several views of the drawings.

My invention in the forms illustrated embodies a casing or housing, within the opposite ends of which are located friction devices, such friction devices being interposed between the opposite ends of a compression-spring and exterior follower-plates, the latter being engaged by the draw-bar and strap or 95 100

yoke connected thereto. The friction devices are brought into frictional contact by a longitudinal movement and are then relatively moved transversely to the line of draft 5 and adjacent devices relatively moved vertically to produce the desired retardation to the movement of the draw-bar relative to the draft-timbers of the car.

Referring more in detail to the views on the sheets of drawings, reference-letter B indicates a portion of the draw-bar, to the enlarged end b of which are secured by suitable fastening devices b' a yoke or strap B'. The draw-gear and buffering apparatus is located 15 within the strap B' and engages suitable stops upon the draft-timbers of the car, whereby the strain either in pulling or buffering is transmitted from the draw-bar B and the straps B' to the draft-timbers of the car 20 through the interposed apparatus, whereby the injurious shocks are reduced or dissipated.

C indicates a casing or housing, which comprises hollow end portions C' and C², preferably rectangular in shape, and side portions connecting the end portions and preferably formed integral therewith.

A series of any desired number of friction devices are located within the end portions 30 of the casing, each series being arranged in two sets H and H', consisting of alternate devices. The exterior friction devices in each series are engaged by followers D' and D², the former of which is interposed between the 35 end of the draw-bar and the hollow end portion C' of the casing, while the latter follower D² is interposed between the loop formed in the strap or yoke B' and the hollow end C² of the casing. The followers D' and D² are provided with reduced portions which engage 40 the exterior friction devices of each series.

Located between the series of friction devices is a compression-spring F, which engages at its opposite ends with the inner friction devices E' and E², respectively, in each 45 series. A smaller compression-spring F' may, if desired, be located within the larger one and may be retained in proper position by means of annular projections extending inwardly from the friction devices E' and E².

Within the hollow end portions C' and C² of the casing are provided guides so arranged as to engage and thereby move one set of the alternate friction devices relatively to the other 55 set of alternate friction devices, and thereby retard the movement of the draw-bar relatively to the draft-timbers of the car. I may provide various arrangements of guides in order to produce the relative movement between the sets of alternate devices. In Figs. 3 and 4, for instance, the interior surfaces of the side walls of the hollow end portions of the casing are provided with guides inclining upwardly from the outer to the inner end of 60 the hollow end portions of the casing. The alternate friction devices of one set—H, for

instance—are provided with reduced side extensions of a vertical height equal to the distance between the guides c' c', while the friction devices of the other set H' are provided with reduced side extensions which do not engage the guides c' c', and consequently are not moved transversely to the line of draft, but merely longitudinally thereof during a pulling or buffering strain. The devices in the set H are moved transversely to the line of draft and vertically with respect to the devices in the second set H' during a buffering or pulling strain, owing to the engagement of their reduced side extensions with the guides c' c', when the friction devices and the end portions of the casing move relatively. 75

In Fig. 5 a modification of the guides within the hollow end portions of the casing is illustrated. In this instance the guides c' c' on 80 one of the interior side walls of the casing are inclined upwardly from the outer to the inner end thereof, while the guides c³ c³ on the opposite inner surface of the casing are inclined downwardly from the outer to the inner end thereof. Consequently when the friction devices of the series H are moved relatively their reduced extensions, through engagement with the guides, cause the devices to be moved vertically upwardly at 85 one side and vertically downwardly at the other side, thereby imparting a slightly rotary motion to the alternate devices in the set H, while the alternate devices in the second set H' are not movable transversely to 90 the line of draft.

Still another modification of the arrangement of guides within the hollow end portions of the casing is illustrated in Fig. 6, in which the relative movement between adjacent friction devices is produced by moving alternate friction devices in both of the two sets. The arrangement of guides in the embodiment of this modification of my invention may be the same as that illustrated in Figs. 3 and 4, in 105

that parallel guides c' c' are provided on each of the opposite interior side walls of the hollow end portions of the casing, such guides inclining upwardly from the outer to the inner ends of the end portions. In addition to 110 the guides referred to other guides are provided upon the interior upper and lower walls of the hollow end portions of the casing, such guides c⁴ c⁴ inclining in a horizontal direction from the outer to the inner ends of the hollow portions of the casing, thereby causing the alternate friction devices in the set H' to be moved transversely to the line of draft and horizontally with respect to the alternate friction devices in the first set H whenever 115 the friction devices and the casing move relatively longitudinally, such relative movement occurring whenever the apparatus is subjected to a buffering or pulling strain. It is of course obvious that the side extensions 120 on the alternate friction devices in the set H' should not engage the vertically-inclined

guides $c' c'$ and also that the reduced extensions on the upper and lower sides of the alternate friction devices in the set H should not engage the horizontally-inclined guides $c^4 c^4$. It is also of course obvious that the alternate friction devices in the set H', which are moved horizontally, should be of a width slightly less than the interior width of the hollow end portions of the casing, so as to permit the horizontal movement of such devices therein. The alternate devices in the set H should also of course be of a height less than the interior height of the hollow end portions of the casing in order that such devices may be moved vertically therein through the engagement of their side extensions with the upwardly-inclined guides $c' c'$.

Figs. 7, 8, and 9 illustrate a further modified arrangement of the guides within the hollow end portions of the casing, in which one set of alternate friction devices in each of the hollow end portions of the casing engage guides which cause the devices to be moved vertically upwardly at one side and vertically downwardly at the other side, while the second set of alternate devices in each of the hollow end portions of the casing is moved horizontally in one direction at the top and horizontally in the other direction at the bottom, thereby imparting a slightly rotary motion in opposite directions to the two sets of friction devices. Guides $c' c'$ on one of the interior side walls of the hollow end portion C' of the casing incline upwardly, while guides $c^3 c^3$, formed on the opposite interior side walls of the end portion C' of the casing, incline downwardly from the outer end toward the center of the casing. These guides are engaged by reduced side portions on the alternate friction devices H and slightly rotate such devices as they are moved longitudinally with respect to the casing. Guides $c^2 c^2$ are located on the interior upper wall of the end portion C' of the casing and incline from right to left, while guides $c^4 c^4$ are formed on the lower interior wall of the end portion C' and incline from left to right. The arrangement of the guides on the interior of the hollow end portion C² is reversed from the arrangement in the hollow end portion C', thereby imparting a slight rotary motion to the sets of alternate devices in opposite directions, so that the inner friction devices of the sets H', which engage the opposite ends of the springs F and F', move transversely in opposite directions, thereby imparting a torsional strain to the springs through their frictional contact therewith.

The operation of my improved draw-gear and buffing apparatus will be readily understood from the foregoing description and is as follows: When a pulling strain is exerted upon the draw-bar B, the yoke B', through its engagement with the follower D², forces the latter against the adjacent friction devices in the hollow end portion C² of the casing, such friction devices being thereby forced

into frictional engagement with each other owing to the tension of the springs F and F' resisting the movement of such devices toward the center of the casing. The opposite follower D' is held immovable with relation to the draft-timbers of the car by means of the stops usually provided for such purpose, and consequently the casing C is bodily moved relatively to the follower D', such movement of the casing being due to the frictional engagement between the extensions on the friction devices and the guides formed upon the interior surfaces of the walls of the hollow end portion C² of the casing. The friction devices within the end portion C' of the casing are consequently subjected to compression between the follower D' and the springs F and F', and thereby forced into frictional engagement with each other. The series of friction devices within both of the end portions C' and C² of the casing are therefore moved relatively to the casing from the positions indicated in Fig. 1 to the positions indicated in Fig. 2. During the relative movement between the friction devices and the casing alternate friction devices are moved transversely to the line of draft and also relatively to the intermediate alternate friction devices owing to the engagement of the extensions on the friction devices with the guides within the end portions of the casing.

The operation of my improved apparatus when a strain is exerted upon the draw-bar in an opposite direction to that described, as when a buffing action occurs, is similar in all respects to the operation above described which takes place when a draw-bar is subjected to a pulling strain, except that the follower D² is held immovable with respect to the draft-timbers of the car by the usual stops, while the follower D' is engaged by the enlarged end b of the draw-bar, and thereby forced in a direction toward the follower-plate D². The relative positions of the parts of the apparatus in buffing would be the same as indicated in Fig. 2, except that the end b of the draw-bar would be in engagement with the follower D', while the strap B' would be moved away from the follower D². When the strain upon the draw-bar is relieved, the follower-plate which has been moved will be gradually returned to its normal position against the stops on the draft-timbers by the expansion of the springs, such expansion also moving the sets of friction devices toward the outer ends of each of the hollow portions of the casing, thereby returning the series of friction-plates through the engagement of their extensions with the guides to their normal positions. No special means are therefore required for restoring the parts of my apparatus to their normal positions, such restoration being accomplished by the expansion of the springs, the compression of which effected the frictional engagement between the series of friction devices.

In the modification of the arrangement of

guides shown in Figs. 7, 8, and 9, in which the alternate friction devices in one set are moved vertically upwardly at one side and vertically downwardly at the other side, while 5 the alternate friction devices in the second set are moved horizontally in one direction at their tops and horizontally in the opposite direction at their bottoms, the spring or springs which engage the inner friction devices are 10 subjected to a slight rotary motion owing to the arrangement of the guides referred to, thereby subjecting the springs to a torsional strain in addition to the compression thereof when the apparatus is in operation, such torsional strain adding slightly to the retardation 15 produced by the relative movement of the adjacent friction devices.

From the foregoing description it is evident that I have produced a draw-gear and buffing apparatus in which a series of friction devices are brought into frictional contact by a longitudinal movement and adjacent devices are then relatively moved transversely to the line of draft and in different angular directions to produce the requisite retardation. It is evident that other arrangements of guides than those illustrated in the drawings within the end portions of the casing might be devised for producing the desired relative movement between adjacent friction devices, and I do not, therefore, wish to limit myself to the specific arrangements of guides herein disclosed.

While I have described more or less precisely the details of construction, I do not wish to be understood as limiting myself thereto, as I contemplate changes in form, the proportion of parts, and the substitution of equivalents, as circumstances may suggest 35 or render expedient without departing from the spirit of my invention.

Having now fully described my invention, what I claim as new, and desire to secure by Letters Patent, is—

45 1. In a draw-gear and buffing apparatus, the combination with a series of friction devices, of means for forcing said devices into frictional engagement, and means for moving one set of alternate devices transversely to 50 the line of draft and angularly with respect to the other set of intermediate alternate devices, substantially as described.

55 2. In a draw-gear and buffing apparatus, the combination with a series of friction devices, of means for forcing said devices into frictional engagement, and means for moving adjacent devices transversely to the line of draft and relatively in different angular directions, substantially as described.

60 3. In a draw-gear and buffing apparatus, the combination with a series of friction devices, of means for forcing said devices into frictional engagement, means for moving one set of alternate devices transversely to the line of draft and vertically with respect to the other set of intermediate devices, and means for moving said second set of alter-

nate devices transversely to the line of draft and horizontally with respect to the said first set of alternate devices, substantially as described. 70

4. In a draw-gear and buffing apparatus, the combination with a series of friction devices, of means for forcing said devices into frictional engagement, and means for moving one set of alternate devices transversely to the line of draft and opposite ends of said devices in opposite directions with relation to the other set of intermediate alternate devices, substantially as described. 75

5. In an apparatus of the class described, the combination with a casing, of friction devices therein, means for forcing said devices into frictional engagement by a longitudinal movement thereof, and means for moving said devices transversely to the line of draft and relatively in different angular directions, substantially as described. 80

6. In a draw-gear and buffing apparatus, the combination with a hollow casing, of guides on the interior surfaces of said casing, friction devices engaging said guides, means for yieldingly resisting the movement of said devices, means for moving said devices longitudinally into frictional contact, said devices being relatively moved transversely to the line of draft, and in different angular directions through their engagement with the guides on the interior surfaces of said casing, substantially as described. 90

7. In a draw-gear and buffing apparatus, the combination with a casing, of guides on the interior surfaces of said casing, of a follower adapted to move relatively to said casing, a compression-spring adapted to resist the movement of said follower, friction devices interposed between said follower and said spring and engaging said guides, whereby the movement of said follower forces said devices into frictional engagement while said devices are moved transversely to the line of draft and relatively in different angular directions through their engagement with said guides, substantially as described. 100

8. In a draw-gear and buffing apparatus, the combination with a casing, of detached friction devices in each end thereof, means for forcing said devices into frictional engagement, and means for moving adjacent devices transversely to the line of draft and relatively in different angular directions, substantially as described. 110

9. In a draw-gear and buffing apparatus, the combination with a casing, of guides on the interior surface of said casing, of a follower adapted to move relatively to said casing, a compression-spring adapted to resist the movement of said follower, friction devices interposed between said follower and said spring and engaging said guides whereby the movement of said follower forces said devices into frictional engagement while one set of alternate devices are moved through their engagement with said guides trans-

versely to the line of draft and opposite ends of said devices in opposite directions with relation to the other set of intermediate alternate devices, said spring being engaged by the adjacent device in said first set of alternate devices and thereby subjected to a torsional strain, substantially as described.

In testimony whereof I sign this specification in the presence of two witnesses.
